Des. 223,954

Patented June 20, 1972

223,954

VEHICLE MARKER LIGHT LENS

Robert I. Nagel, Skokie, Ill., assignor to Triangle Mobile Home Products, Inc., Chicago, Ill.

Filed Oct. 5, 1970, Ser. No. 25,340

Term of patent 14 years

Int. Cl. D26—06
U.S. Cl. D48—32

FIG. 1 is a top plan view of a vehicle marker light lens showing my new design;

FIG. 2 is a side elevational view thereof;

FIG. 3 is a bottom plan view thereof; and

FIG. 4 is a sectional view taken substantially along the line 4—4 of FIG. 1.

I claim:

The ornamental design for a vehicle marker light lens, substantially as shown.
